UNITED STATES PATENT OFFICE

164,434

DOLL

Caroline F. Lougaris, Reno, Nev.

Application December 4, 1950, Serial No. 13,265

Term of patent 14 years

(Cl. D34—4)

To all whom it may concern:

Be it known that I, Caroline F. Lougaris, a citizen of the United States, residing at Reno, in the county of Washoe and State of Nevada, have invented a new, original, and ornamental Design for a Doll, of which the following is a specification, reference being had therein to the accompanying drawing, forming part thereof, in which

Figure 1 is a view in front elevation of a doll, showing my new design.

Figure 2 is a rear view in elevation.

Figure 3 is a fragmentary view in side elevation.

Fig. 4 is a fragmentary, side view of the doll when in a suspended position.

Fig. 5 is a fragmentary, side view of the doll when in a seated position.

I claim:

The ornamental design for a doll, as shown.
CAROLINE F. LOUGARIS.
